UNITED STATES PATENT OFFICE.

PAUL BRANDON BARRINGER, OF BLACKSBURG, VIRGINIA.

FIRE-EXTINGUISHER.

1,085,006.

Specification of Letters Patent.

Patented Jan. 20, 1914.

Application filed February 6, 1913. Serial No. 746,544.

To all whom it may concern:

Be it known that I, PAUL B. BARRINGER, a citizen of the United States, and a resident of Blacksburg, in the county of Montgomery 5 and State of Virginia, have invented a new and Improved Fire-Extinguisher, of which the following is a full, clear, and exact description.

This invention relates generally to fire extinguishers, and more particularly to an improved structure embodying a single container.

The principal object of the invention is to provide a fire extinguisher of simplified construction, adapted to contain a number of 15 solutions or substances for fire extinguishing purposes, the said substances or solutions being maintained separately solely by the differences in the specific gravities thereof.

20 A further object of the invention is to provide a combination of substances for fire extinguishing purposes; that is, tetrachlorid of carbon, carbon dioxid, and sodium bicarbonate in solution, each of which is separated from the others in the normal position of the container, inversion thereof permitting the liquids to mix and be discharged therefrom.

25 In the accompanying sheet of drawings I have shown, by means of a sectional view, the preferred construction of the container, and also the relative arrangement of the fire extinguishing substances therein.

It is true, of course, that the shape of 30 container shown is merely typical of such structures, the inventive idea being satisfied by other containers differing in size and shape to what is disclosed.

35 The container 1 is preferably made of iron or galvanized iron, lead lined iron or copper, provided with an opening 2 adjacent its top, which is normally closed by means of a screw-threaded cap or cover 3 which may be of any particular design or 40 shape. Adjacent the top of the container is an outlet 4 leading through the offset 5, which is connected with a tube or hose 6, the other end of which is preferably provided with a nozzle 7 whereby the elements 45 within the container or casing may be directed where desired when the extinguisher is in use. As shown in the drawings, the nozzle 7 is maintained closely adjacent the outside of the casing by means of oppositely 50 positioned spring clips 8, the lower end of the

nozzle being protected from injury by means of a shelf 9 lying closely adjacent thereto. In order to prevent access of air to the interior of the casing the shelf is provided with a relatively soft element 14 against which the end of the nozzle is maintained by means of the said spring clips. Within the casing, and remote from the lower end thereof, is an end piece 10, preferably pressed to the shape shown, whereby a pocket 11 is provided, and within the pocket is a receptacle 12 which may be made of glass or other suitable material, held in position in any suitable manner, as by means of plaster of Paris or equivalent material.

70 The materials used in the extinguisher comprise sulfuric acid, tetrachlorid of carbon, and a solution of a sodium bicarbonate in water. The sulfuric acid is placed in the receptacle 12 substantially to the height *a*, after which the tetrachlorid of carbon is entered to the height *b*, a sheet of woven wire 13 being positioned on top of the receptacle 12 after the tetrachlorid has reached such a 75 height, the salt solution being placed on top of the tetrachlorid of carbon and substantially to the height *c*. The sheet of woven wire 13 is preferably held in position by means of clips 15, and the central portion of the sheet is provided with an opening 16 whereby filling of the receptacle 12 is facilitated. Due to the difference of specific 80 gravities of these three solutions they will remain separated, as illustrated in the drawings, inverval of the container, however, permitting the acid to mix with the salt solution, generating both heat and carbon dioxid. The heat generated causes rapid 85 expansion of the volatile tetrachlorid of carbon, which, together with the pressure of the carbon dioxid, brings about the rapid discharge of the fluid and gases from the container.

90 A consideration of the drawings and the descriptive matter will make clear the fact that tetrachlorid is used as a sealing agent for the acid and the acid fumes, this same tetrachlorid later serving the function of a fire extinguishing agent; further, the single 95 container holds the combination of the substances or solutions mentioned having their purposes as fire extinguishing compounds, the differences in specific gravities maintaining the solutions separated.

100 The size of the container is, of course, of 110

no essential importance, as modifications may be made in the relative dimensions without departing from the inventive idea.

Having thus described my invention, what

5 I claim as new and desire to secure by Letters Patent is:—

1. In a fire extinguisher, the combination of an acid and a solution of sodium bicarbonate with tetrachlorid of carbon, the tetrachlorid of carbon serving as a sealing agent for preventing mixing of the acid and the said solution.

2. In a fire extinguisher in the form of a single container, the combination of substances which when mixed bring about the generation of carbon dioxid gas, with tetrachlorid of carbon, the tetrachlorid of carbon lying between the said first substances, whereby they are prevented from mixing.

20 3. In a fire extinguisher, the combination of an acid and sodium bicarbonate which

when brought together form carbon dioxid gas, with tetrachlorid of carbon as a sealing agent for preventing mixing of the said acid and salt.

25

4. A fire extinguisher comprising a receptacle having strong sulfuric acid in the lower portion thereof, tetrachlorid of carbon on top of the said acid and the solution of sodium bicarbonate in water on top of the tetrachlorid of carbon, the differences in specific gravities keeping the three substances normally separated and causing their mixture when the receptacle is inverted.

In testimony whereof I have signed my name to this specification in the presence of two subscribing witnesses.

PAUL BRANDON BARRINGER.
